UNITED STATES PATENT OFFICE.

EDWARD ADAM THIELEN, OF DORRANCE, KANSAS.

HOIST.

Application filed September 15, 1927. Serial No. 219,641.

The invention has for its object to provide certain new and useful improvements in hoists of the crane type and it particularly has for its object to provide a hoist of the character disclosed in my application Serial No. 173,736, filed March 8, 1927, of which application the present is in part a continuation thereof.

The present invention has for its object to provide a hoist mechanism which can be used as an automobile jack by removing the crane elements, but which is especially adapted for use as a hoisting crane in automobile garages, repair shops, factories, etc.

With the above and other objects in view that will hereinafter appear, the invention further resides in the novel details of construction, combination and arrangement of parts, all of which will be first fully described, then be particularly pointed out in the appended claims, reference being had to the accompanying drawings, in which:

Figure 1 is a face view illustrating the invention in use.

Figure 2 is an edge view of the parts shown in Figure 1.

Figure 3 is a detail perspective view of the lifting brace and bearing forming member.

Figure 4 is a detail perspective view of the derrick arm and mounting post separated.

Figure 5 is a vertical longitudinal section of another embodiment of my invention.

Figure 6 is a plan view of the same.

Figure 7 is a vertical cross section on the line 7-7 of Figure 5.

Referring now to the embodiment of my invention illustrated in Figures 1 to 4 of the drawings, 1 indicates the base of my improved hoist to which are secured the channel iron side standards 2 in which the slide channels or standards 3 are adapted to be vertically guided.

The base 1 and standards 2 and any suitable brace for holding these parts rigid in the relation shown, together with the lifting and lowering devices later to be described, constitute a stationary unit. The slide standards 3 and the cross brace or platform 4 carried thereby and suitably braced as at 5 constitute a lifting unit.

The lifting head 6 carried at the upper end of a plunger 7 moved by the piston 8

operable in the cylinder 9 is secured to the cross member 4 through the top 10 of which cylinder the said plunger 7 projects.

A suitable fluid duct 11 is provided for admitting fluid under pressure in the cylinder 9 to engage the piston 8 and control lifting and lowering movement of the plunger 7 and head 6. Thus the piston may be said to be part of the stationary unit hereinbefore referred to and the head 6 and plunger and piston 7-8 may be said to constitute a part of the lifting unit hereinbefore referred to.

In carrying out the means embodying my present invention I provide an inverted U-shaped brace member 12, the mounting arms 13 of which are removably insertible in sockets 14 formed in the upper ends of the slide standards 3. The said arms are each provided with a plurality of adjustment holes 15 adapted to receive securing pins 16 insertable through selected ones of the holes and adapted to engage the upper ends of the standards 3 to secure the member 12 at vertically adjusted positions relatively to the said standards.

The member 12 may be equipped with any suitable anti-slip devices, if desired, to facilitate its engagement with an automobile axle for the purpose of elevating the same from a garage floor in association with which the device is mounted.

The member 12 also includes a central bearing aperture 17 to slidably receive the derrick post 18 equipped with a socket 19 at its lower end for rotatably seating upon the upwardly projecting pin 20 carried by the head 6 of plunger 7 to cause the said post 18 to reciprocate vertically with the said plunger 7 guided by the said bearing aperture 17. At its upper extremity the post 18 has secured thereto, through the medium of the pin and slot connection 21, a removable derrick arm 22 provided with a diagonal brace 23 having a socket rest 24 at its lower end adapted to bear against the said post 18.

Referring now to the embodiment of my invention illustrated in Figures 5 to 7 inclusive it will be observed that in this embodiment of the invention the cylinders 28 constitute a pair of standards. These cylinders are connected at the bottom by a supporting bar 29 and at the top by guides 30 secured to the same. The cylinders are also connected at the tops by a suitable connect-

ing bar 31. In order to locate the cylinders 28 rigidly in parallel alignment, suitable braces 32 are provided as indicated.

Furthermore the opening in the floor 6 through which the movable parts of the apparatus project is covered by a plate 33 which is secured to the upper flange 34 of the guides 30. The guides 30 include a cylindrical portion 35 for the piston rods 36 10 that carry the pistons 37. The piston rods in this embodiment of my invention constitute the slide standards. These standards are provided with pin holes 38 to receive safety pins (not shown but similar to pins 15 43 in Figures 5 and 7) to hold the slide standards in position in case the lifting slide line leaks.

The upper ends of the piston rods or slide standards 36 receive the ends 39 of the U-shaped bridge member 40, the latter being preferably of channel iron so as to provide a groove 41 on the upper side in which the axle of an automobile may be received when the apparatus is used simply as an auto jack. 20 The arms 39 of the member 40, like the arms 13 of the member 12, have pin holes 42 to receive the safety pins 43 to support the bridge member 40 on the upper ends of the piston-rod-standards 36 for purpose of 25 30 height adjustment.

In this embodiment of my invention the post 44, which corresponds to the post 18 in the previous embodiment of my invention, is provided with a collar 45 that rests in 35 the channel of the bridge member 40 and the post passes through a bearing 46 in the cylinder supporting bar 31, the bearing 46 being itself provided with bearing balls 47 to constitute a lateral thrust bearing.

40 Fluid is lead to and bled from the cylinders 28 beneath the pistons 37 by a suitable pipe line 48 controlled by a suitable control valve (not shown), similarly to the pipe line 11 of the preceding embodiment of my 45 invention.

From the foregoing description, taken in connection with the accompanying drawings, it is thought that the novel details of construction, the manner of use and the advantages of my invention will be readily 50 apparent to those skilled in the art to which it relates.

What I claim is:

1. In a device of the class described where- 55 in is provided a pair of stationary vertical guide standards, a vertically movable lifting unit including slide standards slidably carried by said guide standards, and slide operating means cooperative with the afore- 60 said structure to lift and lower said lifting unit; said lifting unit's slide standards having sockets in their upper ends, a U-shaped bridge member having portions adapted to be removably received in said sockets, said 65 bridge member having an opening through

the same, a brace member connecting said guide standards having a thrust bearing in alignment with said U-shaped member's opening, and a post provided with a collar and projecting through said opening and bearing with the collar resting on said bridge member, and a derrick arm carried by said post, said post adapted to swivel on its axis for the purposes specified. 70

2. In a device of the class described where- 75 in is provided a stationary unit including vertical guide standards, and a vertically movable lifting unit including vertical slide standards guided by the guide standards, and means to lift and lower said lifting unit; said lifting unit slide standards having sockets in their upper ends, a U-shaped bearing forming member having portions re- 80 movably inserted in said standard socket and having a central derrick post receiving bearing, said lifting and lowering means in- 85 cluding a vertically movable plunger hav- ing a pin projecting vertically therefrom, a derrick post vertically extended through the central bearing and having a socket in its lower end to rotatably seat on said vertically 90 projecting pin, and means at its upper end to make connections with an article to be lifted. 95

3. In a device of the class described where- 100 in is provided a stationary unit including vertical guide standards, and a vertically movable lifting unit including vertical slide standards guided by the guide standards, and means to lift and lower said lifting unit; said lifting unit slide standards having sockets in their upper ends, a U-shaped bearing forming member having portions re- 105 movably inserted in said standard sockets and having a central derrick post receiving bearing, said lifting and lowering means in- 110 cluding a vertically movable plunger having a pin projecting vertically therefrom, a derrick post vertically extended through the central bearing and having a socket in its lower end to rotatably seat on said vertically 115 projecting pin, means at its upper end to make connections with an article to be lifted, and means to vertically adjust the elevation of said U-shaped member. 120

4. In a device of the class described where- 125 in is provided a stationary unit including vertical guide standards, and a vertically movable lifting unit including vertical slide standards guided by the guide standards, 130 means to lift and lower said lifting unit; said lifting unit slide standards having sockets in their upper ends, an inverted U-shaped member having its side arms adapted to be removably received in said standard 135 sockets with its cross portion projecting up- 140 wardly, said member having a plurality of pin receiving holes in the socket received arms thereof, and a central derrick post re- 145 ceiving bearing, pins insertable through 150

selected ones of the holes to engage the tops of the socketed standards and secure the member to adjusted positions, said lifting and lowering means including a vertically 5 movable plunger having a pin projecting vertically therefrom, a derrick post vertically extended through the central bearing and having a socket in its lower end to rotatably seat on said vertically projecting pin, 10 and means at its upper end to make connection with an article to be lifted.

5. In a device of the class described wherein is provided a stationary unit including vertical guide standards, and a vertically 15 movable lifting unit including vertical slide standards guided by the guide standards, and means to lift and lower said lifting unit; said lifting unit slide standards having

sockets in their upper ends, a U-shaped bearing forming member having portions removably inserted in said standard sockets and a central derrick post receiving bearing, said lifting and lowering means including a vertically movable plunger having a pin projecting vertically therefrom, a derrick post vertically extended through the central bearing and having a socket in its lower end to rotatably seat on said vertically projecting pin, a lifting arm removably secured at one end to the upper end of the derrick post and having provision at its other end for connection with articles to be lifted, and a brace secured adjacent the connection equipped end of the lifting arm and extending diagonally downwardly to rest against the derrick post.

EDWARD ADAM THIELEN.
